COMBINATION INDOOR-OUTDOOR THERMOMETER AND HYGROMETER

Gordon W. Florian, Fairfield, Conn., assignor to Taylor Instrument Companies, Rochester, N. Y., a corporation of New York

Application June 11, 1958, Serial No. 51,307

Term of patent 14 years

(Cl. D52—7)

FIG. 2

Fig. 1 is a front view and Fig. 2 is a side view of a combination indoor-outdoor thermometer and hygrometer, showing my new design.

I claim:

The ornamental design for a combination indoor-outdoor thermometer and hygrometer, as shown.
